UNITED STATES PATENT OFFICE.

HERMAN GOTHLBERG, OF ROSELLE PARK, NEW JERSEY.

DESIGN FOR A CHANDELIER-TRIMMING.

10,660.

Specification for Design.

Patented Apr. 26, 1910.

Application filed February 17, 1910. Serial No. 544,526. Term of patent 7 years.

To all whom it may concern:

Be it known that I, HERMAN GOTHLBERG, a citizen of the United States of America, residing at Roselle Park, in the county of Union and State of New Jersey, have invented a new, original, and ornamental Design for Chandelier-Trimming, of which the following is a specification, reference being had to the accompanying drawing, forming part thereof.

Figure 1 is a side-elevation of a chandelier-trimming showing my new design, and Fig. 2 is a plan-view of the same.

I claim:

The ornamental design for a chandelier-trimming, as shown.

HERMAN GOTHLBERG.
